DECORATIVE DEVICE

Filed April 24, 1930

UNITED STATES PATENT OFFICE

LOY J. PALMER, OF EMPORIA, KANSAS

DECORATIVE DEVICE

Application filed April 24, 1930. Serial No. 447,080.

This invention relates to a decorative device, and it is an object of the invention to provide a device of this kind constructed in a manner to permit the inclusion in the assembly of desired illuminating members, such as electric light bulbs.

It is also an object of the invention to provide a device of this kind comprising two members of substantially duplicate construction and design adapted to be assembled in overlying relation, together with illuminating members supported by said assembled members at desired points with respect thereto.

15 The invention consists in the details of construction and in the combination and arrangement of the several parts of my improved decorative device whereby certain important advantages are attained and the device rendered simpler, less expensive and otherwise more convenient and advantageous for use, as will be hereinafter more fully set forth.

The novel features of my invention will 25 hereinafter be definitely claimed.

In order that my invention may be the better understood, I will now proceed to describe the same with reference to the accompanying drawings, wherein:—

30 Figure 1 is a view in side elevation of a decorative device constructed in accordance with an embodiment of my invention;

Figure 2 is a view partly in elevation and partly in section of the device as illustrated 35 in Figure 1;

Figure 3 is a detailed sectional view taken substantially on the line 3—3 of Figure 1;

Figure 4 is a detailed sectional view taken substantially on the line 4—4 of Figure 2;

40 Figure 5 is a view in end elevation of one of the points of the device as illustrated in Figure 1 with the bulb omitted.

The improved device, as herein disclosed, comprises two members A and B of substantially duplicate dimensions and design and each of which being herein illustrated as in simulation of a five pointed star. The marginal portions of the member A are defined by the laterally disposed flanges 1 the outer longitudinal margins of which being con-

tinued by the inwardly disposed flanges 2 substantially at right angles to the flanges 1. The member B is provided with similar flanges 1' and 2' although it is to be noted that the flanges 1 are of such size to completely overlie a flange 1' and to allow the flange 2 to overlie the member B proper. When the members A and B are assembled, it is also to be noted that the flanges 1 and 1' are disposed inwardly and that said members A and B will be maintained spaced apart a distance dependent upon the size of the flanges. The members A and B are also maintained in assembled relation through the medium of a stove bolt 3 or its equivalent 55 coacting with the central portions of said members A and B.

One of the members, as B, is provided at substantially diametrically opposed points with the outstanding loops 4 to accommodate 60 a wire, ring, string or the like to suspend or fasten the device as desired.

The outer ends of the points of the assembled device and the portions thereof between the inner adjacent ends of said points 65 are provided with openings 5 in which are engaged the socket members 6. These members 6 are in electrical connection through the conductors 7 extending along the inner face of the sides of the points with certain 80 of the conductors extending outwardly of the device through an opening 5' for communication with a suitable source of electrical energy. The bulbs 8 engaging within the socket members 6 may be of any kind 85 desired although it is preferred that the bulbs be of differing colors in order to increase the esthetic value of the device when the bulbs are illuminated. The outer surfaces of the members A and B may also be 90 colored in accordance with the effect desired and it is also believed to be obvious that the device may be formed in a design other than that of a star.

From the foregoing description it is 95 thought to be obvious that a decorative device constructed in accordance with my invention is particularly well adapted for use by reason of the convenience and facility with which it may be assembled and em- 100

ployed, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

10 I claim:—

1. A decorative device comprising two members one overlying the other, the marginal portions of the members having inwardly disposed flanges coacting to maintain the marginal portions of the members in spaced relation, means coacting with the central portions of the members for holding the same in assembled relation, and outwardly disposed lamps carried by the flanges of the overlying members.

2. A decorative device comprising two members one overlying the other, the marginal portions of the members having inwardly disposed flanges coacting to maintain the marginal portions of the members in spaced relation, means coacting with the central portions of the members for holding the same in assembled relation, socket members carried by the flanges of the overlying members, conductors positioned between the overlying members and associated with the socket members, and electric bulbs engageable within the socket members.

3. A decorative device comprising two members one overlying the other, the marginal portions of the members being defined by laterally disposed flanges, the outer longitudinal margins of which being continued by inwardly disposed flanges, the first named flanges of the members overlapping each other with the second named flanges of each member overlying the second member, and outwardly disposed illuminating members carried by the flanges of the first named members.

In testimony whereof I hereunto affix my signature.

LOY J. PALMER.
